SOUNDING TOY

Filed Oct. 28, 1948

UNITED STATES PATENT OFFICE

2,534,996

SOUNDING TOY

Henry Singer, Honolulu, Territory of Hawaii, assignor of one-half to John K. Goo Kim, Jr., Honolulu, Territory of Hawaii

Application October 28, 1948, Serial No. 57,113

2 Claims. (Cl. 46—177)

1

This invention relates to a toy gun, and it is primarily an object of the invention to provide a device of this kind which, when "fired," operates a whistle in lieu of detonating a cap or discharging a missile.

Another object of the invention is to provide a toy of this kind wherein the body of the toy carries one or more whistles and wherein the hand grip of the device is deflatable for sounding the whistle.

A further object of the invention is to provide a device of this kind including a revolving cylinder carrying a plurality of whistles, each of a tone different from the others and wherein each of the whistles is selectively sounded.

Other objects and advantages will be apparent during the course of the following description.

In the accompanying drawings forming a part of this application, and in which like numerals are employed to designate like parts throughout the same:

Figure 1 is a side elevational view of the toy gun, with parts broken away and in section, according to the present invention;

Figure 2 is an enlarged sectional view taken on the line 2—2 of Figure 1;

Figure 3 is a fragmentary side elevational view of a modified toy gun with parts broken away and in section;

Figure 4 is an enlarged sectional view taken on the line 4—4 of Figure 3.

Referring in detail to Figures 1 and 2 of the drawings, the numeral 10 designates a toy gun body preferably fabricated of suitable metal. Projecting forwardly from the body 10 is a tubular barrel 11 having a front sight 12 thereon. The gun body 10 is provided with a cut-out 13 extending inwardly from its rear end, and the body 10 is shaped to define an inwardly-turned flange 14.

A deflatable handle 15 preferably fabricated of suitable rubber has its front end enlarged to provide suitable shoulders 16. The front end of the handle 15 is positioned within the cut-out 13 so that the flange 14 on the body 10 coacts with the shoulders 16 to insure a sturdy connection between the body and handle.

The body 10 is also provided with a recess or chamber 17 which is arranged forwardly of the cut-out 13, there being a partition 21 separating the cut-out 13 and recess 17. A pin or shaft 18 extends across the recess 17 and has its ends rotatably supported in the gun body 10. Mounted on the pin 18 is a cylinder 19 provided with a plurality of spaced, parallel whistles 20, and each

2

whistle 20 is of a different tone from the others.

The partition 21 is provided with an aperture 22 and seated in the aperture 22 is a small open-ended tube 23. One end of the tube 23 projects into the handle 15 and is held therein by a flange 24. The other end of the tube 23 is bent back to define a flange 25 for preventing longitudinal shifting of the tube.

Each of the whistles 20 is provided with an inlet orifice 26 which is adapted to be moved into registry with the open-ended tube 23 as the cylinder 19 is revolved or rotated. The whistles 20 further include openings 27 for the egress therethrough of air. A spring 28 is interposed between the front end of the cylinder 19, and the gun body 10 for normally biasing the whistle inlet orifice 26 to form an air-tight passage against the tube 23.

For manually-rotating the cylinder 19, a plurality of radially-disposed, spaced tabs 29 project from the exterior of the cylinder 19, the tabs 29 corresponding in number to the whistles 20 and the tabs are provided with suitable markings thereon indicating the different whistle tones.

In Figures 3 and 4, there is shown a toy gun provided with a single whistle 35, and comprises a body 30 having its exterior configuration resembling a "six-shooter." The body 30 has a stationary or fixed cylinder 40 and the body 30 is provided with a socket 31 in its rear for receiving the front portion of a resilient handle 32, there being flanges 33 depending from the gun body 30 and coacting with shoulders 34 on the handle 32 for insuring a firm connection between the handle and gun body. A whistle 35 is supported on the gun body 30, and an open-ended tube 36 connects the handle 32 to the inlet orifice 37 of the whistle 35 for conveying air to the latter when the handle 32 is deflated or squeezed. An opening 38 is formed in the top of the gun body 30 and registers with the outlet orifice 39 of the whistle 35 for the egress therethrough of air.

From the foregoing, it will be apparent that a toy musical gun has been provided which, when "fired," operates a whistle in lieu of detonating a cap or discharging a missile.

In Figures 1 and 2, a plurality of different toned whistles 20 are provided, and to sound any of these whistles the user need only exert a left-hand thumb pressure (broken lines) on the tabs 29 so as to thereby depress the spring 28 and simultaneously revolve the cylinder 19 in either direction until the inlet orifice 26 of the whistle 20 registers with the open-ended tube 23. Then,

as the handle 15 is deflated, the whistle will sound.

In Figures 3 and 4, the toy gun is provided with a single whistle 35 which is sounded as the user deflates the resilient handle 32.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In a sounding toy, a body having the form of a revolver including a frame and a barrel, a hand grip in the form of a collapsible bulb attached to the rear side of said frame, an air duct opening through the rear side of said frame and communicating with the interior of said hand grip, a cylinder mounted for rotation on a horizontal axis within said frame and having a circular series of bores opening longitudinally through the same adjacent the periphery thereof, and tubular whistles fitted in said bores and having different tonal characteristics, said whistles having tone sounding vents opening outwardly

thereof and through the periphery of said cylinder and blow vents opening through the rearwardly directed ends of the same, said blow vents being selectively aligned with said air duct when a turning motion is imparted to said cylinder.

2. The invention as defined in claim 1, with a longitudinally extending rib formed on the periphery of said cylinder in centered relation with respect to each two adjacent of the whistles and constituting finger-pieces to facilitate the turning of the cylinder to selectively position said whistles relatively to the said air duct.

HENRY SINGER.
